UNITED STATES PATENT OFFICE

1,984,085

EDGE ROAD MARKER

David E. Ross, La Fayette, Ind., assignor to
 Purdue Research Foundation, La Fayette, Ind.,
 a corporation of Indiana

Application November 16, 1933, Serial No. 698,367

6 Claims. (Cl. 88—1)

This invention relates to traffic lane markers of the general type shown in Ross U. S. Patents Nos. 1,927,756 and 1,927,757, such markers being intended to be placed in or along dividing lines 5 of traffic in a roadway so that rays of light from the headlights of an automobile will "pick up" the markers and be reflected thereby in such manner that the driver of the automobile can readily distinguish the part of the road on 10 which he can safely travel.

The present invention is an edge road marker adapted to be secured upon the surface of the roadway along the edge thereof, to define the side of the road so that the driver can avoid 15 running off the road.

My novel edge road marker is illustrated in the accompanying drawing, and will be explained in connection therewith, and the novel features thereof for which protection is desired 20 summarized in the claims.

In said drawing:—

Fig. 1 is a top view of my edge road marker.

Fig. 2 is a bottom view thereof.

Fig. 3 is a side view thereof.

Fig. 4 is a longitudinal section thereof on the 25 line 4—4, Fig. 1, and

Fig. 5 is a transverse section on the line 5—5, Fig. 1.

The marker shown is designed to be placed 30 on the outer edge of a roadway, and has a body 1 which somewhat resembles a clam shell in plan, having a thick butt portion 1a at rear and a diverging fan like front portion 1b which tapers downwardly from the butt portion toward the front and sides as indicated, and projects at each end 1c slightly beyond the butt. The body may be provided with a hole 1e at 35 about the center of the front portion 1b for the passage of a lag screw (not shown) or other suitable means may be used for fastening the marker in position. From the rear side of the body depends a spike or member 1w which may be bifurcated as shown, or of other preferred form. This spike is adapted to be embedded in 40 the roadway adjacent the edge thereof.

The butt end of the body is preferably recessed on its underside, as shown at 1g in Figs. 2 and 4, and in each end of the butt 1a is an opening 1f for the reception of a reflecting lens, which may be of any suitable construction. 45 Preferably I use glass lenses 2 having their inner ends silvered, and their outer ends convex; the inner portion of the lens being slightly larger than the outer portion thereof which should fit neatly within the opening 1f. After the lenses

are inserted in the openings the recess may be filled with a suitable plastic material, indicated at 3, which when hardened will retain the lenses securely in position. The construction is such that the lenses 2 are protected on all sides. 5 The outer ends of the reflectors are protected from injury by the projecting portion of the ends of the butt, indicated at 1h and by the adjacent projecting portions 1c of the front tapered portion of the body.

To define the outer edge or paved side line of a roadway a series of such markers are placed along such edge, and at night the lens in such markers will reflect back rays from the headlights of approaching automobiles and clearly 10 define the edge of the roadway so that the drivers will be able to avoid running off the road in the darkness.

The utility of such markers will be obvious 15 from the foregoing description.

I claim:—

1. An edge road marker comprising a body having a thick longitudinal butt portion at rear and a front portion curving downwardly and outwardly from the butt portion, said butt having an opening in its end the axis of the opening being substantially parallel with the plane of the outer side of the butt portion, and a reflecting lens in said opening adapted to reflect the light of an automobile approaching 20 that end of said butt portion.

2. An edge road marker comprising a body having a thick longitudinal butt portion at rear and a front portion curving downwardly and outwardly from the butt portion, the ends 25 of the front portion extending slightly beyond the adjacent ends of the butt portion, said butt having an opening in its end, the axis of the opening being substantially parallel with the plane of the outer side of the butt portion, and a reflecting lens in said opening adapted to reflect the light of an automobile approaching 30 that end of said butt portion.

3. An edge road marker comprising a body having a thick longitudinal butt portion at rear, 35 a front portion curving downwardly and outwardly from the butt portion and a downwardly extending fastening member or spike at its rear side adapted to be embedded in the roadway, said butt having an opening in its end the axis 40 of the opening being substantially parallel with the plane of the outer side of the butt portion; and a reflecting lens in said opening adapted to reflect the light of an automobile approaching 45 that end of said butt portion.

4. An edge road marker comprising an approximately shell shaped body having a thick longitudinal rear butt portion, and a front portion curving downwardly and outwardly from the butt portion, the ends of the front portion extending slightly beyond the adjacent ends of the butt portion and a downwardly extending member adapted to be embedded in the roadway; said butt having an opening in each end, the axes of the openings being substantially parallel with the plane of the outer side of the butt portion, and a reflecting lens in each opening.

5. An edge road marker comprising an approximately shell shaped body having a thick longitudinal butt portion at rear, a front portion curving downwardly and outwardly from the butt portion, and a downwardly extending spike below the butt adapted to be embedded in the roadway; said body having a recess in its underside and said butt having an opening in each end, the axes of the openings being substantially parallel with the plane of the outer side of

the butt portion; a lens in each of said openings adapted to reflect the light of an approaching automobile; the ends of said front portion extending slightly beyond the adjacent ends of the butt portion near the openings therein.

6. An edge road marker comprising an approximately shell shaped body having a thick longitudinal butt portion at rear, a front portion curving downwardly and outwardly from the butt portion and a downwardly extending spike below the butt adapted to be embedded in the roadway; said body having a recess in its underside, and said butt having openings in each end, the axes of the openings being substantially parallel with the plane of the outer side of the butt portion, and a lens in each of said openings adapted to reflect the light of an automobile approaching that end of said butt portion.

DAVID E. ROSS.
